Filed Jan. 19, 1962, Ser. No. 68,373

Term of patent 3½ years

(Cl. D13—1)

FIG. 1.

FIG. 2.

FIG. 3.

FIG. 4.

For convenience of illustration only parts of the brick surfaces have been shown in the several views on the drawing. It is to be understood that these surfaces continue throughout the plain areas shown.

I claim:

The ornamental design for a dwelling, as shown and described.
